ORE JIG

Bjorn R. Storsand, San Francisco, Calif.

Application October 3, 1933, Serial No. 691,941

1 Claim. (Cl. 209—457)

The invention generally relates to the concentration of materials and more particularly pertains to a device for effecting complete and rapid separation of values from ore bearing sands and gravel.

5 The jig of my invention is especially designed for wet concentration processes and is particularly suitable for use in connection with dredging operations for the recovery of gold, platinum, 10 or other values. However, the device readily is adaptable for use in other environments.

An object of the invention is to provide an ore 15 concentrator which affords uniform application of washing fluid to the material supplied thereto as well as substantially unobstructed paths for the settling of separated values.

A further object of the invention is to provide a 20 jig of the aforementioned type which is characterized by its rigid, yet simple construction and its relatively few moving parts.

A still further object of the invention is to provide 25 an improved ore concentrator which is inexpensive to manufacture and operate and which requires but a minimum of attention during operation.

Another object of the invention is to provide a 30 relatively light weight jig especially suitable for dredge work and characterized by the small volume of water contained therein.

The foregoing objects are attained in the embodiment 35 of the invention which is illustrated in the accompanying drawing, as will appear from the following description of the device.

Referring to the drawing:

Figure 1 is a front sectional elevation of a portion 40 of the embodiment of the invention showing one complete cell and a portion of an adjoining cell.

Figure 2 is an end sectional elevation of the 45 embodiment of the invention which is illustrated in Figure 1, and taken on the section line 2—2 thereof.

In its preferred form the ore jig of my invention 50 preferably comprises a framework partitioned to provide a plurality of compartments or cells, a sieve supported in each cell for receiving material, and a water tank consisting of two connected relatively movable sections disposed in each cell below said sieves, together with means for reciprocating one section of each of said tanks whereby the water therein is pulsated and forced upward intermittently through each sieve, the pulsations of the water being transmitted directly against and uniformly 55 over the underside of each sieve.

As illustrated in the drawing, I provide an open framework, generally designated by the reference numeral 11, which is preferably fabricated of angle irons 12 to provide a rigid construction. The framework is of generally rectangular shape 5 and at spaced intervals longitudinally thereof I provide additional angle irons 13 to divide the framework into two or more compartments or cells 14. It is to be understood, of course, that a one cell jig of the character hereinafter described 10 can be employed and is within the scope of the invention.

Each cell of the jig of my invention includes a water or hutch tank 16 of two relatively movable connected sections 17 and 18 and also includes a sieve 19 for receiving the material from which values are separated, each sieve 19 conveniently being supported upon a grate 21 supported within the tank adjacent to the mouth 22 thereof. The mesh of the sieve 19 is dependent 20 upon the material to be worked. In the embodiment of the invention illustrated, the upper section 17 of each of the tanks 16 is rigidly fastened to the angles 12 and 13 of the framework, adjoining upper sections 17 having a common 25 wall 23 serving as a partition between adjoining cells 14.

While any desired form of hutch tanks 16 may be utilized, I preferably employ a tank having an upper section 17 which is formed with a substantially 30 rectangular mouth and with a substantially circular outlet 24, this construction being afforded by forming the upper portion of section 17 with a substantially straight wall and the lower portion of the section with a converging wall 26. 35 The bottom portion of this section may be formed integral with the remaining portion of section 17 or can be separate therefrom, as shown, and spot welded or otherwise rigidly fastened thereto. The lower section 18 of the tank 16 preferably is formed to a substantially inverted frustoconical shape with a relatively large inlet 27 and a relatively small outlet 28. The sections 17 and 18 of the tank conveniently are connected together for relative movement by flexible means, 40 such as a strip of rubber 29 of generally U-shape in cross-section or by any other flexible material which is impervious to water, together with ring clamps 30 and screw bolts 31. The connection, as illustrated in the drawing, preferably is made 45 by clamping the rubber member 29 between each ring clamp 30 and the flanges of the lower and upper sections of the tank 16 by tightening the bolts 31 which pierce the flanges and the ring clamps. With a connection of this character, 50

it is a comparatively simple and easy job of assembling the sections or of disassembling the tank sections for replacing a worn rubber member 29, when needed.

- 5 The drawing illustrates my jig as used on placer dredges wherein the dredged material, prior to jigging, passes over saving tables or sluices, not shown. A relatively large volume of water is usually added to the dredge material 10 while passing over the tables, and this mixture of water and material flows to the jig to be received upon the sieves 19 thereof, the material settling from the water to form jig beds 34. As illustrated, the sieve 19, of the jig cell which is 15 adjacent to the source of the material, that is, adjacent to the saving tables, is supported therein at a higher level than the sieve of the next or adjoining cell so that the stream of material and water spills from one cell to another. The extended lateral walls of the upper sections 17 of the hutch tanks 16 serve as weirs for the advancing stream of water and material. A tailboard 35 is affixed to the last cell of the jig for guiding the discharging tailings to launders, not shown. 20
- 25 In accordance with the invention, means are provided for reciprocating the lower sections or bottoms 18 of each hutch tank in order to impart pulsations to the water contained therein. These means include a shaft 37 which is journaled in 30 bearings 38 supported on beams 39 of the frame and which is substantially coextensive with the length of the frame. Suitable means, such as a motor, together with a belt and pulleys, also not shown, may be employed for driving the shaft. 35
- 35 The reciprocating means also includes connections between the shaft 37 and the bottoms 18 of each tank. In the embodiment of the invention illustrated, these connections include a casting 41 supported below each tank bottom 18 and to 40 which the tank bottom is welded or otherwise securely fastened, together with a cross-head 42 connected to each casting, an eccentric strap 43 fastened, by means of a wrist pin 44, to each cross-head, and eccentrics 46 carried by the shaft 37 45 and upon which the straps 43 are mounted. Preferably, the cross-heads are formed integral with the casting 41 and each cross-head is slidably mounted in guides 47 carried by longitudinally extending beams 49 and 51 of the frame. Actuation of the shaft 37 causes reciprocation of the several tank bottoms 18 through the connections just described. Eccentrics with adjustable strokes may be utilized in order to vary the rate of reciprocation and consequent rate of pulsation of the water in the tanks 16. The castings 41 are each provided with outlets 52 and 53 for the concentrate and launders 54 or other conveying means can be loosely fastened to the outlets for carrying away the separated values. As shown, plugs 56 can be used to close the outlets 52 and 53 when desired.

Water is supplied to each of the hutch tanks

16 by pipes 57, each of which is provided with a check valve 58. Preferably the check valves 58 are arranged to close upon the upward stroke of the lower sections 18 of the hutch tanks and to open upon the downward or suction stroke of such sections thereby to admit water freely to the tanks on the downward strokes. With this arrangement, the material of the jig beds 34 is forced abruptly upwardly on the pulsion or upward strokes of the sections 18 but the material settles 10 more gradually during the downward strokes to filter through the sieves 19. The separated values pass through the sieves 19 to the lower sections 18 of the tanks and pass to the castings 41 where the concentrates are drawn off as desired. It will be observed that the path of the separated values is substantially unobstructed in the jig of my invention, the jig having no diaphragm or other flat means spanning the hatches for pulsating the water and upon which the separated values may come to rest. 15 20

In order that the pulsating water may be applied uniformly over the underside of the jig beds 34, baffles or guides may be inserted in the hutch tanks 16 for giving direction to the pulsated water. These baffles may take the form of fins which can be welded to the inner surface of the upper sections 17 of the tank or can be, as illustrated, a frusto-conical guide plate or band 59 supported by means of braces 61 within the tank. As the water is forced upwardly by the bottom sections 18, a portion thereof is guided by the bands 59 toward the outer portions of the jig beds 34 while another portion of the water is directed toward the central portions of the jig 35 beds. 30

While I have illustrated the preferred embodiment of my invention in the accompanying drawing, it is to be understood that I am not to be limited to the embodiment shown, as my invention, as defined in the appended claims, can be embodied in a plurality of forms. 40

I claim:

In an ore jig, a stationary tank having an opening in its lower end, the opening being substantially in a horizontal plane, a stationary jig bed carried within the upper part of the tank, baffle means carried within the tank above said lower opening but below the jig bed, a downwardly convergent bottom container disposed directly below the opening in the tank, the upper end of the bottom container having an opening similar in contour to the lower opening in the tank, an outwardly bulged flexible wall section serving to form a flexible sealed joint between the lower edge of the tank and the adjacent upper edge of the bottom container, means serving to guide the bottom container for movement in a vertical direction, and means disposed exteriorly of the tank and the bottom container for reciprocating the bottom container in a vertical direction. 50 55 60

BJORN R. STORSAND.
